DESIGN FOR A SPOON

Lake Phillips Srygley, Fort Worth, Tex.

Application November 7, 1944, Serial No. 116,202

Term of patent 14 years

(Cl. D54—12)

To all whom it may concern:

Be it known that I, Lake Phillips Srygley, a citizen of the United States of America, residing at Fort Worth, in the county of Tarrant and State of Texas, have invented a new, original, and ornamental Design for a Spoon, of which the following is a specification, reference being had to the accompanying drawing, forming a part thereof.

In the drawing:

Figure 1 shows a top plan view of a spoon embodying my new device.

Figure 2 is a side elevational view of the same.

Figure 3 is a front elevational view of the same. The dominant features of my design are shown in full lines in the drawing.

I claim:

The ornamental design for a spoon, as shown and described.

LAKE PHILLIPS SRYGLEY.
